US0D1008025S

(12) **United States Design Patent** (10) **Patent No.:** **US D1,008,025 S**
(45) **Date of Patent:** **** Dec. 19, 2023**

(54) **COMPARTMENTED CARTON INSERT**

(71) Applicant: **Inno-Pak, LLC**, Delaware, OH (US)

(72) Inventors: **Jonathan D. Sill**, Delaware, OH (US);
Steven A. Mayer, Indianapolis, IN (US)

(73) Assignee: **Inno-Pak, LLC**, Delaware, OH (US)

(***) Term: **15 Years**

(21) Appl. No.: **29/836,356**

(22) Filed: **Apr. 26, 2022**

Related U.S. Application Data

(62) Division of application No. 29/708,963, filed on Oct. 10, 2019, now Pat. No. Des. 952,465, which is a (Continued)

(57) **CLAIM**

The ornamental design for a compartmented carton insert, as shown and described.

DESCRIPTION

FIG. 1 is a perspective view of a first embodiment of a compartmented carton insert showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof, showing the compartmented carton insert in use with an exemplary carton;

FIG. 9 is a perspective view of a second embodiment of a compartmented carton insert, showing our new design;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof; and,

FIG. 16 is another perspective view thereof, showing the compartmented carton insert in use with an exemplary carton.

The dash-dash broken lines are shown for the purpose of illustrating environmental subject matter of an exemplary carton and form no part of the claimed design.
